US00D821648S

(12) **United States Design Patent** (10) **Patent No.:** **US D821,648 S**
(45) **Date of Patent:** **** Jun. 26, 2018**

(54) **COMB**

(71) Applicant: **Shenzhen Mexi Technology Co., Ltd.**,
Shenzhen, Guangdong Province (CN)

(72) Inventor: **Jihai Qiu**, Guangdong Province (CN)

(73) Assignee: **SHENZHEN MEXI TECHNOLOGY CO., LTD.**, Guangdong Province (CN)

(**) Term: **15 Years**

(21) Appl. No.: **29/554,235**

(22) Filed: **Feb. 9, 2016**

(51) LOC (11) Cl. **28-03**
(52) U.S. Cl. **D28/25**

(57) **CLAIM**

The ornamental design for a comb, as shown and described.

DESCRIPTION

The file of this patent contains at least one drawing executed in color. Copies of this patent with color drawing(s) will be provided by the Office upon request and payment of the necessary fee.

FIG. 1 is a front view of a comb;

FIG. 2 is an enlarged left view of the comb;

FIG. 3 is a perspective view of the comb;

FIG. 4 is a rear view of the comb;

FIG. 5 is an enlarged right view of the comb;

FIG. 6 is a top view of the comb; and,

FIG. 7 is a bottom plan view of the comb.

The broken lines shown in FIGS. 1-7 depict portions of the comb that form no part of the claimed design.
